UNITED STATES PATENT OFFICE.

VINCENT BENDIX, OF CHICAGO, ILLINOIS.

ENGINE STARTER.

Application filed April 6, 1921. Serial No. 459,037.

To all whom it may concern:

Be it known that I, VINCENT BENDIX, a citizen of the United States, residing at Chicago, in the county of Cook and State 5 of Illinois, have invented certain new and useful Improvements in Engine Starters, of which the following is a specification.

My invention has relation to engine starters for starting or cranking internal 10 combustion engines, and the like, and more particularly to that part of the starter known as the drive or transmission for operatively connecting between the prime mover, such as an electric motor, and a part of the engine 15 to be started such as the flywheel thereof with which such drive is caused to engage. The object of my invention is to provide a simple and efficient form of drive which operates automatically for engagement 20 and for engagement purposes and which embodies novel and advantageous features in construction and mode of operation.

In the drawing Fig. 1 is an elevation partly in section of an engine starter embodying 25 my invention, Figs. 2 and 3 sections on the lines 2—2 and 3—3 of Fig. 1 and Fig. 4 a view similar to Fig. 1 but illustrating a modified form of construction.

My invention may be embodied in different forms and types of drives without departing from the spirit of my invention. For instance while my invention is shown in connection with a drive of the direct or 30 single reduction type and also of the inboard type, it will be understood that my invention is applicable to the indirect or so-called double reduction type and also to the outboard type.

Referring to the particular embodiment 40 of my invention shown in Figs. 1 and 2, the starting motor 1 is provided with an extended armature shaft 2 whose outer end is journaled in the bearing 3. The driving member which is here a pinion 4 is mounted 45 on the shaft 2 for longitudinal movement thereof and rotary movement therewith. In the present instance the pinion is adapted for automatic engagement with and disengagement from a member of the engine to be started and for the purposes of its said longitudinal and rotary movements on the shaft, such pinion is threaded on the screw threaded portion 5 of the shaft. The pinion 50 when moved longitudinally to the left, Fig.

1, is adapted to mesh with the teeth 7 of the engine member which is here a flywheel 8.

The pinion is normally pressed with a yielding pressure (while in its normal position shown in full lines) in a direction towards the flywheel teeth but the same is restrained by an operating means which is under the control of the operator. The yielding means which tends to force the pinion into mesh with the flywheel is a coiled spring 9 encircling the shaft 2 and bearing at one end against the outer or right hand end of the pinion and at its other end against the collar 10 which is secured to the shaft 60 2 in suitable manner as by the pin 11. When the pinion is in normal position as shown in Fig. 1 this spring 9 is under compression and tends to force the pinion into mesh with the flywheel whenever the restraining influence, hereinafter described, is relieved, so that the spring can expand.

The means for controlling the action of the spring 9 consists of an actuating rod or plunger 12 which here extends through the 80 dashboard 13 of an automobile and more particularly through a hole 14 in a plate 15 which is fastened to such board. This rod also has its bearing in a bracket 16 anchored to and extending inward from the dashboard. The inner end of the rod 12 is bifurcated so as to provide a shifting yoke 17 terminating in inturned rollers 18 which are received within the circumferential groove 19 formed by the two circular flanges 20 at the 85 outer end of the pinion 4. This rod 12 is detachably locked in its outward position in suitable manner. In the present instance this locking means consists of a shoulder 21 on the upper side of the rod adapted to engage the upper side of the hole 14 and held thereagainst by means of the spring 22 bearing against the lower side of the rod 12.

When the parts are in the normal position shown in Fig. 1, the rod 12 is held in 100 its outward position (shown in full lines) by said locking means and consequently the spring 9 which is in compressed condition, is prevented from expanding and from shifting the pinion into mesh with the flywheel. However, when the operator operates the rod 12 by depressing the handle 23 and thereby releases it from the lock, such rod will be shifted inwardly by the expanding 105 action of the spring 9. As a result, the 110

pinion 4 will be moved automatically into mesh with the flywheel as shown in dotted lines in Fig. 1.

In the present instance, the rod 12 serves the additional purpose of actuating a switch for the current to the starting motor and the construction herein shown is preferably so arranged that the motor will begin to rotate and thereby start to rotate the pinion 4, just before the latter reaches the flywheel teeth, thereby assuring the proper meshing of the pinion teeth and the flywheel teeth.

Referring to the electrical switch details, the bracket 16 is provided with the two electrical contacts 24 which are arranged parallel to each other and in the path of movement of a connector 25 secured to and extending upwardly from the rod 12 and adapted to have a wiping contact between the two contacts 24. These contacts are electrically connected by the wires 26-26 with the motor 1.

Describing a cycle of operation and starting with the parts in their normal position shown in Fig. 1, the operator depresses merely the handle 23, thereby unlocking the rod 12 and permitting the spring 9 to shift the rod inwardly and against the stop 5^a and consequently to shift the pinion 4 to the left into mesh with the flywheel teeth. In this action the pinion is slightly rotated by the cooperation of its threads with the screw shaft and moreover, just before the pinion reaches the flywheel teeth, the connector 25 will close the motor circuit and start the motor and its shaft into rotation, thereby facilitating the meshing of the pinion teeth and the flywheel teeth. The flywheel will now be rotated and when the engine starts on its own power, the pinion will be automatically demeshed by reason of the excess speed of rotation imparted thereto by the flywheel, whereupon the pinion will be moved longitudinally to the right against the pressure of the spring 9. The rod 12 will likewise be shifted to the right and when such rod reaches its normal position, the locking means will operate to hold it in said position as shown in Fig. 1.

The construction shown in Fig. 4 is the same as that of Fig. 1 with the exception of the location of the spring 27 which is here associated directly with the rod 12 instead of directly with the shaft 2. However, the general action of this modified form is the same as that above described.

I claim:

1. An engine starter drive including a rotatable shaft, a driving member mounted thereon for longitudinal movement thereof and rotary movement therewith, and adapted for automatic engagement with and automatic disengagement from a member of the engine to be started, means tending to shift the driving member into engagement with

such engine member, said driving member being mounted to rotate on the shaft as an incident to such longitudinal shifting by said means, and mechanism for restraining such means.

2. An engine starter drive including a rotatable shaft, a driving member mounted thereon for longitudinal movement thereof and rotary movement therewith, and adapted for automatic engagement with the automatic disengagement from a member of the engine to be started, yielding means tending to shift the driving member into engagement with such engine member, said driving member being mounted to rotate on the shaft as an incident to such longitudinal shifting by said means, and mechanism for restraining such means.

3. An engine starter drive including a rotatable shaft, a driving member mounted thereon for longitudinal movement thereof and rotary movement therewith, and adapted for automatic engagement with and automatic disengagement from a member of the engine to be started, a spring tending to shift the driving member into engagement with such engine member, said driving member being mounted to rotate on the shaft as an incident to such longitudinal shifting by said means, and mechanism for restraining such means.

4. An engine starter drive including a rotatable shaft, a driving member mounted thereon for longitudinal movement thereof and rotary movement therewith, and adapted for automatic engagement with and automatic disengagement from a member of the engine to be started, an electric motor including electrical connections and switch, said motor being operatively connected with the shaft, means tending to shift the driving member into engagement with the engine member, and combined mechanism for restraining such means and for operating such switch.

5. An engine starter drive including a rotatable shaft, a driving member mounted thereon for longitudinal movement thereof and rotary movement therewith, and adapted for automatic engagement with and automatic disengagement from a member of the engine to be started, an electric motor including electrical connections and switch, said motor being operatively connected with the shaft, a spring normally compressed when the driving member is in normal position and by its expansion tending to shift such member into engagement with the engine member, and combined mechanism for restraining the expansion action of such spring and for operating such switch.

6. An engine starter drive including a rotatable shaft, a driving member mounted thereon for longitudinal movement thereof and rotary movement therewith, and adapt-

- ed for automatic engagement with and automatic disengagement from a member of the engine to be started, an electric motor including electrical connections and switch, 5 said motor being operatively connected with the shaft, a spring normally compressed when the driving member is in normal position and by its expansion tending to shift such member into engagement with the engine member, mechanism for restraining the expansion action of such spring and for operating such switch, and means for locking such mechanism in normal position.
7. An engine starter drive including a rotatable screw threaded shaft, a driving member threaded thereon for rotary movement therewith and for automatic longitudinal movement thereof in both directions for engagement with and disengagement from a 10 member of the engine to be started, means tending to shift the driving member into engagement with such engine member, and mechanism for restraining such means.
8. An engine starter drive including a rotatable screw threaded shaft, a driving member threaded thereon for rotary movement therewith and for automatic longitudinal movement thereof in both directions for engagement with and disengagement from a 15 member of the engine to be started, a spring tending to shift the driving member into engagement with the engine member, and mechanism for restraining the action of such spring.
9. An engine starter drive including a rotatable shaft, a driving member mounted thereon for longitudinal movement thereof and rotary movement therewith, and adapt- 20 ed for automatic engagement with and automatic disengagement from a member of the engine to be started, an electric motor including electrical connections and switch, 25 said motor being operatively connected with the shaft, means tending to shift the driving member into engagement with the engine member, and combined mechanism for restraining such means and for operating such switch, just prior to the engagement between the driving and engine members.
10. An engine starter drive including a 30 rotatable screw threaded shaft, a driving member threaded thereon for rotary movement therewith and for automatic longitudinal movement thereof in both directions for engagement with and disengagement from a member of the engine to be started, an electrical motor including electrical connections and switch, means tending to shift the driving member into engagement with such engine member, and mechanism for restraining such means, comprising a movable yoke cooperating with the driving member, and carrying a device for operating the switch.
11. An engine starter drive including a 35 rotatable screw threaded shaft, a pinion threaded thereon and adapted to engage and drive a member of the engine to be started, such pinion having at one end a circumferential groove, a coiled spring acting on the pinion to urge it towards the engine member, 40 and a hand controlled rod terminating at one end in a yoke cooperating with said groove and adapted to normally restrain the movement of the pinion towards the engine member.

VINCENT BENDIX.
